UNITED STATES PATENT OFFICE.

RICHARD C. ELLIOTT, OF MANCHESTER, ENGLAND, ASSIGNOR TO THE MERGENTHALER LINOTYPE COMPANY, OF NEW YORK, N. Y.

MAGAZINE FOR LINOTYPE OR ANALOGOUS MACHINES.

SPECIFICATION forming part of Letters Patent No. 635,998, dated October 31, 1899.

Application filed December 24, 1897. Serial No. 663,329. (No model.)

To all whom it may concern:

Be it known that I, RICHARD CORNELIUS ELLIOTT, a subject of the Queen of the United Kingdom of Great Britain and Ireland, formerly of Highfield Cottage, No. 8 Wellington road, Hounslow, London, in the county of Middlesex, but now of No. 11 Hulme street, Oxford street, Manchester, in the county of Lancaster, England, have invented certain new and useful Improvements in and Connected with the Detachable and Adjustable Magazines of Linotype and Analogous Machines, (for which I have obtained the following patent: Great Britain and Ireland, No. 9,570, dated April 14, 1897;) and I do hereby declare that the following is a full, clear, and exact description of the invention, reference being made to the accompanying drawings, which are to be taken as part of this specification and read therewith, and one which will enable others skilled in the art to which it appertains to make and use the same.

The first part of the present invention relates to the escapement mechanisms of linotype and analogous machines, but more especially to the escapement mechanisms of such magazines as are detachable, while the second part of it relates to an arrangement of magazines adjustable for the substitution 30 of one of them for another.

The invention is especially applicable to the well-known Mergenthaler linotype-machine, that being the one for which it has been developed. For that reason principally and also because it is the only linotype-machine at present in use in this country the form which it takes when made up for use on that machine has been selected for detailed illustration and specification.

40 The machine last mentioned is described in detail in the specification of United States Letters Patent No. 436,532, of 1890. The charged magazine of that machine was detachable as a whole from the machine-frame.

45 Letters Patent No. 548,432 describe a machine in which the two or more magazines, laid one on top of another and secured together, are made adjustable vertically in order to bring one magazine or another into 50 operative relation at the lower end to the escapement devices fixed on the main frame

and at the upper end in operative relation to the distributing devices which deliver the matrices to the magazine.

For convenience of reference the adjustable magazines connected in series will be designated as "multiple" magazines.

The trigger devices or escapements of the selecting mechanism of the last-mentioned specification are carried by the machine-frame. They are situated sufficiently far in front of the mouths of the magazines proper for each to engage and hold two matrices, one behind the other, both of which matrices have been already discharged from the respective groove in the magazine proper on their way to the assembling-block. Those remaining in any magazine proper are prevented from dropping through the mouths thereof by a special stop, such as a rod standing in front of that mouth. Consequently each time that one magazine proper is to be substituted for the one then registering with the top and bottom there are two matrices from each of its grooves standing in the said bottom under the control of the escapements. All of those matrices must be withdrawn from the bottom and sent through the machine through the distributor, so as to be returned to the respective magazine proper before the substitution can be effected. Further, he must withdraw two matrices from each groove in the substituted magazine before he can begin composition from the substituted font.

The substitution of one magazine proper for another of a series is described as effected by a manually-operated shaft carrying a pair of worms gearing with as many worm-wheels, which have incorporated with them internally-screw-threaded nuts engaging with a pair of screws depending symmetrically from the frame which supports the said adjustable arrangement of magazines.

The object of the first part of the invention is the prevention of the loss of time due to the above-mentioned withdrawals, and of the second, mechanism operated by the machine for effecting the substitution of one magazine for another.

Referring to the accompanying drawings, which are to be taken as part of this specification and read therewith, Figure 1 is a sec-

tional side elevation of an adjustable arrangement of magazines, illustrating both parts of the invention; Fig. 2, a detail section through a pair of matrix-grooves of a detachable magazine, illustrating the first part of the invention. It is taken along the line 2 2 of Fig. 3. Fig. 3 is a section taken along the line 3 3 of Fig. 2; Fig. 4, a section taken along the line 4 4 of Fig. 5 and illustrates a modification of the first part of the invention; Fig. 5, a detail sectional side elevation taken along the line 5 5 of Fig. 4; Fig. 6, a detail sectional side elevation taken along the line 6 6 of Fig. 4; Fig. 7, a plan of the escapement push-rods of Figs. 4, 5, and 6; and Fig. 8, a sectional plan taken along the line 8 8 of Fig. 1 and illustrates the second part of the invention. Fig. 9 is a vertical section through one of the screws for raising and lowering the magazine. Fig. 10 is a view of the modified or alternative detail.

A A are parts of the main frame of the machine; B B, magazines; B' B², the magazine top and bottom, respectively; B⁵ B⁵, the pair of adjusting-screws; B⁶ B⁶, the internally-screw-threaded nuts; B⁷ B⁷, the worm-wheels; B⁸ B⁸, the worms; B⁹, the worm-shaft; B¹² B¹², tenons fast to and depending from the magazine-support and sliding in mortises B¹⁰ B¹⁰, fast to the main frame A; b b', the bottom and top plates, respectively, of each magazine; b² b², the matrix-grooves therein; b¹³, the support for the series of magazines; E, one of the series of escapement-rods; F, the respective escapement or matrix-trigger; f' f², the escapement-pallets; G, the vertical channel down which the matrices drop after they have passed their respective escapements, and Y Y matrices.

40 Each of the foregoing parts is substantially the same as heretofore.

The three magazines of Fig. 1 are rigidly connected or united, so that they form jointly a multiple magazine which is adjustable bodily up and down, carrying with it the escapements or matrix-releasing devices, which maintain their relations to their respective matrix-channels. The single magazines of Figs. 2 to 7 are detachable only—i. e., without adjustability.

55 According to the first part of the invention there is an escapement or matrix-trigger F for each matrix-groove b², and their pivots f⁵ are immediately under the respective magazine instead of being in front of it.

The connection between each escapement-rod E and the respective escapement F is by means of an escapement push-rod adapted to be actuated by the said escapement-rod 60 through a suitable connection and to be returned by a suitable spring.

65 The connection between the escapement-rod E and the push-rod above mentioned is necessarily of an easy self engaging and disengageable type to allow of such engagement or disengagement taking place automatically at each substitution. For that reason I pre-

fer a push-rod held by the idle position of the escapement-rod E opposite to and aligned with the escapement push-rod and beyond the magazine—i. e., just clear of the plane of severance between the magazine B on the one side and the magazine front B² on the other.

E²¹ is the push-rod in question. Its nose is preferably coned to facilitate its engagement with the escapement push-rod described farther on. It is held to the escapement-rod E by a toggle-joint, the links E²² E²³ of which are held to each other and to the top of the escapement-rod E by a pivot common to the three. The free end of the link E²² is pivoted upon the adjacent wall of the channel G and that of its fellow link E²³ to the front end of the push-rod E²¹. The toggle-joint just described may be replaced by a bell-crank lever, as shown in Fig. 10.

E²⁴ is a guide for the motion of a push-rod E²¹. It is fast to the under side of the magazine front B².

E²⁵ is a spring to prevent the nose of each push-rod E²¹ dropping away to the front from the position above described.

E²⁶ is a fixed horizontal perforated plate acting as a guide for the top ends of the escapement-rods E.

F' F² are two straight inclines on the bottom edge of the escapement and meeting at an internal angle in the middle of the length of that edge. In either of the terminal positions of an escapement the nose of one pallet f' or f² is as much higher than the other as is the extremity of the opposite incline below that of the other.

F³ is a chamber between the bottom plate b of one magazine proper and the top plate b' of the one beneath it in the case of an adjustable magazine or between the bottom plate b and an additional plate b² in the case of a detachable magazine, as shown in Figs. 2 to 7.

F⁴ is an escapement push-rod. It stands in the chamber F³ with its front end flush with the front edge of the magazine B and with its opposite end bearing against the front incline F' and standing clear of the rear one F². The object of this relative position between the rear end of the rod F⁴ and the said inclines is to keep the pallet f' in the path of the front matrix Y, as heretofore.

F⁵ is a returning-spring adapted to return the rod F⁴ to its normal position after each actuation of it by the escapement-rod E.

The first part of the invention works as follows: Premising that it is the upward motion of an escapement-rod E that frees a matrix Y, when one of the rods E rises its vertical motion is converted into an oblique one in the push-rod E²¹ by the toggle-joint long enough to push the rear end of the escapement push-rod F⁴ past the pivot of the escapement F and along the rear incline F², thereby rocking the escapement F on its pivot, with the usual result to the column of matrices Y in the groove b², more particularly to the leading one. As soon as that escapement-

rod E drops the returning-spring F⁵ returns the escapement push-rod F⁴ to its normal position, likewise with the usual result to the said column of matrices, more particularly

5 to the then leading one. The front end of an escapement push-rod F⁴ has a conical indentation F¹⁵ in it to receive the opposite end of the push-rod E²¹, if that is coned.

It is obvious that the details of this first 10 part of the invention may be varied without departing from the essential features of it, the only essential requirement being that the reciprocation of the rod F⁴ shall cause the vibration of the escapement F.

15 Referring to Figs. 2 and 3, each escapement push-rod F⁴ works in a guide-block F⁶, held in position by being screwed into a plate F⁷, extending across the front of the chamber F⁸. The returning-spring F⁵ stands within a chamber F⁸, formed within the guide-block F⁶ and about the rod F⁴, pushing from the inner end of the chamber F⁸ as a base and against a collar F⁹ on the said rod F⁴. The guide-block F⁶ is made in two parts screwed together, as indicated, to allow of the insertion of the spring F⁵. The inner end of the rod F⁴ is segmental, standing up above the other portion of the rod to make room for the downward portion of the front half of the escapement.

30 Referring to Figs. 4 to 7, the escapement push-rods F⁴ are flat and edge up. They have enlargements F¹⁰ on one edge at the front end for the conical indentations F¹⁵. Being 35 flat they take up less room laterally than the shape illustrated in Figs. 1, 2, and 3, and space is further economized by setting them with the enlargements F¹⁰ alternately at the top and bottom of the chamber F⁸, as shown 40 in Fig. 4, so that the usual distances between the columns of matrices Y are not increased. A flat rod F⁴ slides in grooves F¹¹ in both top and bottom of the chamber F⁸, and its rear end is turned upward to engage with the escapement F and shaped to allow of the rocking motion of the latter. The returning-spring F⁵ stands, of course, behind the respective enlargement F¹⁰ and works between an abutment F¹² and the said enlargement.

45 That abutment is on the top or bottom plate of the chamber F⁸, according to the position of the enlargement F¹⁰ in that chamber. The front plate F⁷ is dispensed with, a bar F⁴ being held in the chamber F⁸ against the push 50 of the spring F⁵ by a piece F¹³, fast on the top or bottom plate of that chamber, according to the position of the enlargement F¹⁰ and spring F⁵. F¹⁴ is a longitudinal slot along the bar F⁴, wide enough to allow of the front 55 end of the said bar being compressed, so as to pass between the piece F¹³ and the opposite plate of the chamber F⁸ on its insertion into the latter. The resilience of the front portions of the said bar on each side of the 60 slot F¹⁴ separates them after such insertion. As many of the abutments F¹² as are on the bottom plate of the chamber F⁸ serve as guides

or lateral supports for the motion of as many of the bars F⁴ as are intermediate thereof and may serve as rests for the rear ends of 70 the other bars F⁴ to slide upon. (See Fig. 7.)

According to the second part of the invention the worm-shaft is capable of receiving a constant motion of rotation, and there is interposed between each worm-wheel and nut 75 a combination of three pulleys, one coaxial with the worm-wheel, another with the nut, and the other either running idle or as a reversing-pulley. In the type of gearing illustrated the worm-shaft B⁹, (see Figs. 1 and 8,) 80 carrying the two worms B⁸, is mounted in a carriage B⁵⁵, capable of a reciprocating motion parallel with the matrix-grooves b² by reason of the engagement of the soles of it in grooves B⁵⁶ in a suitable bracket-like portion of the 85 machine-frame arranged there for that purpose. That shaft is driven constantly in the same direction by a belt B⁵⁷, running around a pulley fast on it, and which belt B⁵⁷ derives its motion from some convenient rotating 90 member of the machine. B⁵⁸ is a friction-pulley fast on the axis of each worm-wheel B⁷. Each of the screws B⁵ is made fast to the magazine-support b¹³, as heretofore; but its thread is of the opposite hand to that of its fellow 95 for a reason that will be self-evident directly. It revolves in bearings in special extensions of the main frame A, and there is concentrically incorporated with its nut B⁶ a friction-pulley B⁵⁹. B⁶⁰ is a second friction-pulley of 100 the same diameter as B⁵⁹, turning in bearings in special extensions of the main frame A. The four pulleys B⁵⁹ B⁶⁰ are in the same plane as the pulleys B⁵⁸, and each pulley B⁶⁰ engages with the respective pulley B⁵⁹. The pulleys 105 B⁵⁸ are rather smaller than those B⁵⁹ B⁶⁰ and are so positioned in the carriage B⁵⁵ that they engage with either the pulleys B⁵⁹ or with the pulleys B⁶⁰ or stand clear of both, according to the position of that carriage.

110 The carriage B⁵⁵ receives its motion from a hand-lever B⁶¹, which is held to it by a stud B⁶², standing up from the middle of the carriage top and through the lever. The fulcrum of the latter is not included in the figures. It 115 may occupy any suitable position and be of any suitable type consistent with the lever's moving the carriage B⁵⁵ along the grooves B⁵⁶ in either direction. So long as the pulleys B⁵⁸ are clear of both pairs of pulleys B⁵⁹ B⁶⁰ the 120 adjustable magazine is at rest. Pulling the carriage B⁵⁵ over to the front of the machine engages the pulleys B⁵⁸ with the front pulleys B⁵⁹ and B⁶⁰ and causes the rise or fall of the 125 adjustable magazine, according to the direction in which the belt B⁵⁷ is running. Pushing it backward as far as it will go engages the pulleys B⁵⁸ with the rear pulleys B⁶⁰ and B⁵⁹ and results in the motion of the adjustable magazine in the opposite direction. Putting it in an intermediate position disengages the pulleys B⁵⁸ from all the pulleys and leaves the said magazine at rest.

130 The invention is not limited to the type of

gearing illustrated, but includes any other substantially similar in respect of its capacity for direct or reverse driving or for being out of gear, according to the position of the hand-lever which controls the position of the carriage.

Leading features of my invention, broadly new in a machine having a multiple movable magazine or reservoir, are, first, the fixed relation between the escapements or releasing devices and the channels with which they coöperate in the movable magazine, so that although an escapement may be connected with different finger-keys as the magazine is moved each escapement operates always in connection with the same channel in the magazine; second, the construction and arrangement of the escapements in the movable magazine so that they retain matrices at the extreme end of the magazine, thus avoiding a waste of space and leaving the matrices in position for immediate discharge under each new adjustment of the magazine, and, third, the connection of the magazine-adjusting devices with the driving mechanism of the machine so that the magazine may be raised or lowered quickly and without requiring any considerable effort on the part of the operator.

Having thus described my invention, what I claim is—

- 30 1. In a linotype or analogous machine, an adjustable magazine, carrying escapement devices and spring-controlled push-rods to actuate them, in combination with a main frame provided with devices to abut against and actuate one series or another of the push-rods, according to the position in which the magazine is adjusted.
- 35 2. In a linotype and in combination, a main frame, an inclined vertically-adjustable magazine comprising a series of magazines lying one over another, escapement devices mounted in and carried by the magazine, one for each channel, a push-rod in connection with each escapement, key-rods in the main frame and devices connected therewith for operating one or another series of the push-rods of the magazine, according to the adjustment of the latter.
- 40 3. A magazine for a linotype-machine, having a series of matrix-channels extended therethrough from end to end, in order that the matrices may pass through and out of the

magazine in a straight line, in combination with escapement devices mounted therein and adapted to hold the matrices at the extreme delivery end of the magazine, and escapement-operating devices carried by and movable lengthwise of the magazine and exposed at its lower end, whereby the magazine is adapted to be moved past the stationary keyboard connections in the machine.

4. In a linotype-machine, the multiple magazine, having open-ended channels for the direct delivery of the matrices and escapements for each channel, such escapements adapted to retain matrices at the extreme end of the magazine, in combination with mechanism for raising and lowering the magazine, and escapement-operating devices mounted in the main frame and adapted to automatically connect with the escapements of one section or another as the adjustment of the magazine is changed.

5. In a linotype-machine, a multiple magazine having open-ended channels for the delivery of the matrices, in combination with escapement devices for each channel, located within the end of the magazine, in combination with means for raising and lowering the magazine bodily, a single series of finger-key connections adapted to coöperate with one series of escapements or another according to the adjustment of the magazine, and a stationary receiver G, into which the matrices are delivered under all adjustments of the magazine.

6. In a linotype-machine, the combination of a multiple magazine, mechanism for raising and lowering the same, power driving mechanism, and intermediate reversible connections through which the raising and lowering mechanism may be stopped and started at will.

7. In a linotype-machine, a multiple magazine, adjusting-screws therefor, a driving-pulley and intermediate reversible connections between said pulley and screws.

In witness whereof I have hereunto affixed my signature, in presence of two witnesses, this 6th day of December, 1897.

RICHARD C. ELLIOTT.
